UNITED STATES PATENT OFFICE.

PETER J. NAGLE, OF ROCHESTER, NEW YORK, ASSIGNOR TO CEDAROID CO. INC., OF ROCHESTER, NEW YORK, A CORPORATION.

BOX.

1,288,131.

Specification of Letters Patent.

Patented Dec. 17, 1918.

Application filed April 15, 1918. Serial No. 228,585.

To all whom it may concern:

Be it known that I, PETER J. NAGLE, a citizen of the United States, and resident of Rochester, in the county of Monroe and 5 State of New York, have invented certain new and useful Improvements in Boxes, of which the following is a specification.

The present invention relates to boxes, and more particularly to the type made from 10 paper board and having a hinged closure or cover overlapping the top edge of the front wall of the box, an object of this invention being to provide for utilizing an ordinary barbed brad or nail for securing the cover 15 to the front wall without separating the layers of the front wall so that the fastener becomes loose.

To this and other ends, the invention consists of certain parts and combinations of 20 parts all of which will be hereinafter described, the novel features being pointed out in the appended claim.

In the drawings:—

Figure 1 is a perspective view of a box 25 embodying this invention, the border being broken away to show the nail anchoring device;

Fig. 2 is an enlarged section showing the manner in which the nail is driven into the 30 anchoring device;

Fig. 3 is a perspective view of the anchoring device before it is applied to the box; and

Fig. 4 is a detail view showing the anchoring device in front elevation applied to the 35 box.

The scarcity of cedar wood has increased the use of paper board in the making of cigar boxes. With the use of paper board 40 the fastening of the box covers has been a problem, due to the fact that the small nails or brads used for securing the covers will separate the laminations of the paper board and not secure the cover to the front wall. 45 To overcome this objection this invention combines with the box an anchoring device

which will support the sides of the front wall so that a nail driven into the front wall will not destroy the latter and will at the same time be firmly held, although permitting its withdrawal when desired.

In the illustrated embodiment of the invention, the box body 1 and its hinged cover 2 are both made from paper board, the cover overlapping the front wall of the body as is 50 usual in boxes of this type. On the upper edge of the front wall, the anchoring device 3 is fitted. This device 3 comprises a channeled strip made from thin sheet metal stock with the sides of the channel lying on 55 opposite sides of the front wall and secured to the latter preferably by forming spurs or inwardly bent projections 4 on the device 60 penetrating the paper wall. Preferably also this strip is narrow so that the border strip 65 5 usually employed for ornamenting cigar boxes will cover such anchoring strip. The nail 6, preferably barbed, is driven through the cover near the edge of the latter and passes through the top wall of the anchoring 70 device into the paper front wall. In passing through the anchoring device the latter is deflected inwardly about the nail, as at 7, and this deflected portion, together with the 75 barbs or spurs on the nail, firmly secure the latter against accidental removal, while at the same time permitting the nail to be withdrawn by force. The depending sides of the channel member support the front wall 80 against destruction by the nail.

What I claim as my invention and desire to secure by Letters Patent is:—

In a box having a front wall made of paper board, and a hinged cover overlapping the front wall, a channeled nail anchoring strip of thin metallic stock secured over the upper edge of the front wall and having its sides secured to the said front wall, and a nail passed through the cover and through the uppermost portion of the strip into the 90 paper front wall.

PETER J. NAGLE.
